SPRAY GUN

Harold A. Roselund, Toledo, Ohio, assignor to
The De Vilbiss Company, Toledo, Ohio, a corporation of Ohio

Application May 22, 1933, Serial No. 672,240

3 Claims. (Cl. 299—89)

This invention relates to a spray gun adapted to be attached directly to a small receptacle containing material to be sprayed, and to be carried in the hand while it is used. Compressed air is supplied to the gun by a small air compressor and is controlled by a trigger which first opens the air valve and then the liquid valve. A part of the air stream is directed through the nozzle, while the remainder serves to build up a pressure within the receptacle.

A spray gun of this type is adapted to be supported and manipulated by one hand and, in order that it may not be too heavy, it should be made, as far as practicable, from aluminum. Aluminum, however, is too soft to be advantageously used for both sides of the threaded connection between the top of the receptacle and the cap to which the spray nozzle is connected.

One object of the invention, therefore, is to provide a spray gun comprising a liquid container and a cap therefor, both composed chiefly of aluminum and having a threaded connection that is reinforced by a collar of zinc, zinc alloy or similar metal which is materially harder than the aluminum.

Another object of the invention is to provide means for effectively preventing any solid particles of the spray material from splashing or being otherwise carried into the air chamber of the nozzle and clogging it. For this purpose, the air chamber of the nozzle is separated from the upper portion of the receptacle by a packing of copper wool or other porous, non-corrodible material.

The above and other objects of the invention will be more fully explained in the following detail description, taken in connection with the accompanying drawing, in which—

Fig. 1 is a vertical longitudinal section of a spray gun constructed according to the invention;

Fig. 2 is an enlarged sectional view taken on the line 2—2 of Fig. 1;

Fig. 3 is a partial section taken on the line 3—3 of Fig. 1;

Fig. 4 is a detail view of an air cap which may be used interchangeably with that shown in Fig. 1.

Fig. 5 is an enlarged section of the air cap and associated parts.

The spray gun to which the invention relates comprises a barrel 5 formed at its rear end with a hand grip 6 in front of which is a trigger 7 pivotally connected to the barrel, as shown at 8. The front end 9 of the barrel has an air cap 10 secured thereto by a suitable union 11. Compressed air is supplied by a small air compressor to the barrel

5 through a port 12 and an air valve 13 controls the flow of the compressed air through a bore 14 to an air chamber 15 in the front end of the gun from which a portion of the compressed air is emitted through the cap 10 along with the liquid coating material which is emitted through an inner liquid nozzle 16. The flow of liquid from the bottom of the receptacle through a conduit 17 is controlled by a needle valve 18 which is associated with the liquid nozzle 16. The operation of the spray gun, therefore, is effected through the medium of the trigger 7 which, as it is pulled back toward the grip 6, first engages the head 19 of the air valve 13 to open it against the resistance of its spring 20, and then engages the head 21 of the needle valve to open it against the resistance of its spring 22.

The rear end of the gun is pivotally connected at 23 to the receptacle cap 24, which is formed centrally with an upwardly disposed hollow extension or neck 25 terminating in a tapered annular seat 26. The barrel 5 is formed with a correspondingly tapered portion 27 which engages the seat 26. The underside of the cap 24 is formed with an annular seat 28 which is adapted to receive a plate 29. The liquid conduit 17, which is secured to the barrel 5, has a downward extension 30 secured to its lower end by a suitable union 31. A nut 32 in threaded engagement with the nipple 30 secures the plate 29 to its seat 28 and at the same time secures the tapered enlargement 27 30 of the gun barrel to the tapered seat 26.

A bore 33 connects the air chamber 15 with the cavity 34 within the cap extension 25 and communicates with the interior of the receptacle 35 through one or more perforations 36 formed 35 in the plate 29. When the gun is in operation, therefore, a part of the compressed air passes from the chamber 15 through the air cap 10, while the remainder of the compressed air flows through the bore 33, cavity 34 and ports 36 and 40 serves to build up a pressure within the receptacle 35. In order that the spray material may not pass into the air chamber 15 to clog up the nozzle, the cavity 34 is filled with copper wool or equivalent material which constitutes an efficient filter.

In spray guns of this type it is customary for the cap 24 to have a screw threaded connection with the top of the receptacle 35. For the sake of lightness, it is desirable to make the gun and the receptacle chiefly of aluminum. This metal, however, is not adapted to be used for both sides of the threaded connection because of the possibility of mutilation of the threads due to the softness of the metal. One side of this connec- 55

tion, therefore, is reinforced by a collar or ring 37 of harder metal, such as zinc or zinc alloy. According to the present construction, this ring 37 is fitted over the top of the receptacle 35 and 5 the edge of the receptacle top is then flattened over the upper edge of the ring to form a smooth seat against which rests the gasket 38 within the rim 39 of the cap 24. In order to prevent the ring 37 from turning with relation to the receptacle top, the ring is formed with notches 40 in its upper inner edge, and the receptacle top is formed with lugs which fit therein.

In order that the flow of air through the cap 10 may be accurately determined with relation 15 to the pressure upon the liquid within the receptacle 35, the air for atomizing is caused to pass through metering holes 41, usually four in number, which may be bored with the utmost accuracy through an annular flange 41^a provided on 20 the liquid nozzle 16 short of its tip portion, which latter is also preferably tapered.

The forward end of the gun barrel is cylindrically bored to form the chamber 15, and the cap 10 has its rear or inner end of cylindrical form 25 of a size to fit into the outer end portion of the bore forming said chamber. The cap 10 is provided in its inner end with the customary cavity for receiving the liquid nozzle 16 and the bottom of such cavity is conical to adapt it to 30 have a tapered seat against the outer tapered edge of the nozzle flange 41^a. It is important in the spray heads of guns of this character to have the cap member accurately aligned in coaxial relation to the liquid nozzle, and it is found in 35 practice that such centering is effectively accomplished by having the rear end of the nozzle of cylindrical form and fitted into a cylindrical recess of the barrel and to cause the bottom of the cap cavity to have a tapered seat against a 40 conical portion of the liquid nozzle, such, for instance, as the flange 41^a. By this arrangement, a tightening of the union 11 causes a true centering of the members 10 and 16 when the parts are in assembled operating relation. The im- 45 portance of this is emphasized in a spray gun having a rotatably adjustable cap member which may necessitate frequent loosening of the union 11 for cap adjustment purposes.

In certain situations, as for example, in painting a ceiling, with the receptacle 35 nearly full of paint, it is desirable to adjust not only the angle of discharge but also the plane of the fan spray, so that it will not be necessary to tip the receptacle enough to permit the paint to flow 50 through the ports 36. For this reason, it is preferred to construct the air cap as shown in Fig. 1. In such construction the discharge bore of the cap 10 seats closely on the tapered tip of the liquid nozzle 16 and is provided with passage- 55 ways 42 through which the metered air from the holes 41 passes. The cap 10 is also formed with a laterally inclined seat 43, to which a tip 44 is secured by a union nut 45. Thus by loosening the nut 11, the cap 10 may be adjusted circum- 60 ferentially to cause the flow to be diverted in any direction desired and by loosening the nut 45 the tip 44 may be adjusted circumferentially to vary the plane of the fan shaped spray emitted from the slit 46 in the tip 44. A standard air cap 10^a, 65 as shown in Fig. 4, may, however, be used interchangeably with the cap 10.

By the construction above described I have produced a spray gun which is inexpensive, yet durable, and which is extremely light and easily manipulated. The cap seats firmly on the receptacle and the gun barrel is seated firmly on 5 the cap so that there is no leakage of the spray material. The packing within the cap prevents the escape of any spray material into the air chamber and this packing may be easily renewed whenever necessary.

Although I have shown and described in detail a specific form of the invention, it is to be understood that this is merely illustrative and may be modified considerably without departing from the scope of the appended claims.

What is claimed is:—

1. A spray gun comprising a liquid receptacle, a cap releasably mounted on said receptacle and having a gasket portion seating on the receptacle end and provided at its central top portion with 20 a hollow upward extension, said extension being open at its top and provided with a conical seat and having a seat at its base portion, a gun body having a conical portion seating on the conical seat of said extension and having a liquid supply 25 tube extending down through said extension and into the receptacle, a plate received by said tube within the receptacle and seating at its edge against the seat at the base of said cap extension, said plate having openings between the receptacle 30 and the hollow of said extension, a nut threaded on said tube and bearing against said plate to effect opposed clamping coaction of the gun body and plate against their respective seats at opposite ends of the cap extension, said gun body having an air passage in communication with the hollow of said extension.

2. In a spray gun, a barrel body having a chamber in its forward end, a liquid passage and an air passage in communication with the chamber, a liquid nozzle carried by the body and having a conical tip communicating with said liquid passage and having a conical portion rearwardly of its tip, which conical portion is formed with air passages extending therethrough, an air cap for 45 said chamber rotatably mounted on the body and having a cavity in its rear into which the liquid nozzle projects and having an air passageway in communication with the air passages of said conical portion of the nozzle and therethrough with 50 the chamber, said cavity having a tapered portion spaced rearwardly of the tip of the nozzle and seated against the conical portion of the nozzle and having a liquid discharge passage receiving the conical tip of the nozzle, and releasable means engaged with the body and with the air cap for drawing the latter against the conical portion of the nozzle and simultaneously therewith drawing the conical tip of the nozzle against the walls defining the liquid passage of the air 55 cap.

3. A spray gun in accordance with claim 2 wherein the air cap is provided with an angular tip portion having a common discharge passageway communicating with the respective air and liquid discharge passages of the air cap, said common discharge passageway discharging angularly with respect to the air and liquid discharge 65 passages of the air cap.
